UNITED STATES PATENT OFFICE.

ALFRED H. HUMPHREY, OF NEW YORK, N. Y.

GAS-LAMP.

No. 841,323.

Specification of Letters Patent.

Patented Jan. 15, 1907.

Application filed November 16, 1905. Serial No. 287,653.

To all whom it may concern:

Be it known that I, ALFRED H. HUMPHREY, a citizen of the United States, residing at New York city, in the State of New York, have invented certain new and useful Improvements in Gas-Lamps, of which the following is a specification.

This invention relates to improvements in gas-lamps.

The objects of this invention are, first, to provide an improved gas-lamp having an inverted burner or burners; second, to provide an improved gas-lamp having a plurality of inverted burners in which all of the burners are accessible and capable of independent adjustment; third, to provide an improved gas-lamp in which the burner or burners are properly supplied with air and at the same time are fully protected; fourth, to provide an improved gas-lamp having an inverted burner or burners in which the liability of back lighting is reduced to a minimum; fifth, to provide an improved gas-lamp in which the parts are effectively protected from excessive heat from the burners; sixth, to provide in a gas-lamp having an inverted burner or burners an improved globe and shade support; seventh, to provide in a gas-lamp an improved pilot-light and means for flashing the same; eighth, to provide in a gas-lamp an improved valve mechanism; ninth, to provide in a gas-lamp having an inverted burner an improved mantle-support.

Further objects and objects relating to structural details will definitely appear from the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

Figure 1 is a detail vertical section taken on a line corresponding to line 1 1 of Fig. 2 of my improved gas-lamp. Fig. 2 is a horizontal section taken on a line corresponding to line 2 2 of Fig. 1. Fig. 3 is an enlarged detail vertical section taken on a line corresponding to line 3 3 of Fig. 1, showing structural details and the arrangement of the burners.

Fig. 4 is an enlarged detail vertical section taken on a line corresponding to line 4 4 of Fig. 1, showing structural details of the

valve mechanism. Fig. 5 is a detail section taken on line 5 5 of Fig. 4. Fig. 6 is a plan of the mantle-support.

In the drawings similar letters of reference refer to similar parts throughout the several views, and the sectional views are taken looking in the direction of the little arrows at the ends of the section-lines.

Referring to the drawings, the chimney A is arranged centrally in the lamp. The chimney A is preferably provided with a downwardly-flaring flange A' at its lower end. This chimney is preferably supported by straps a, which connect the same to the coupling C' for attaching the lamp to the gas-supply pipe, as C. The coupling C' is preferably T-shaped in form and is connected to the gas-delivery ring B of the burners by the pipe C''. A pipe C''' is provided for the other arm of the coupling C'; but this is preferably a blind pipe, so that only one valve, as D, is required to control the delivery of the gas, and at the same time the valve is located close to the burners.

The gas-delivery ring is provided with threaded bosses b'' on its under side to receive the delivery-nozzles b'. The burner-tubes B' are threaded on these nozzles. The burner-tubes are provided with suitable air-ports at the base opening about the delivery-nozzles and are arranged through suitable holes provided therefor in the flange A' of the chimney, so that the burners B'' are located beneath the flange, as clearly appears from the drawings. A needle-valve b is provided for each nozzle to control the delivery of gas therefrom. These valves are preferably arranged through the tube, suitable threaded openings being formed therein, as is indicated in Fig. 3 of the drawings. By this means the delivery of gas to the burners can be independently adjusted.

The valve D is located, preferably, just above the gas-delivery ring B. (See Fig. 1.) This valve is provided with a main passage d and an auxiliary passage e'' for supplying gas to the pilot for flashing the same. The pilot E, which is placed in an inverted position, is provided with a laterally-directed tip E', projecting under the flange of the chimney. The tip is arranged to direct the jet laterally between the burners, so that when flashed they are all ignited thereby.

The pilot E is connected to the connecting-pipe C' by the passage e, opening into the same above the main valve D. A needle-

valve, as e'' , is provided for regulating the supply of gas through this passage:

The valve D is operated by the lever D', which is connected thereto by means of the pawl D''' on the lever and the ratchet-wheel D'' on the valve. By this connection by successive pulls on the lever the valve is continuously rotated in one direction. The ratchet-wheel D'' is provided with four teeth, so that one actuation of the lever turns the gas on and the succeeding actuation shuts it off, each actuation giving the valve a quarter-turn. A chain d'' is connected to the lever for convenience in manipulation, the chain depending to some point within convenient reach. The lever D' is returned to its initial position by the coiled spring d'''.

The auxiliary passage e'' is so arranged in relation to the main passage that as the valve is turned to its open position the auxiliary passage is brought into registry with the passage e', admitting gas to the pilot for flashing the same. This occurs when the main valve is only partially open, so that when it is fully open the auxiliary passage e'' is closed. By locating the main valve at a point close to the ring B gas is delivered to the main burners promptly, so that a sufficient supply is at hand for lighting by the flash-pilot.

A globe-supporting ring F, having an outwardly and downwardly turned rim F' at the top adapted to receive the rim of the globe, is mounted upon the flange A' of the chimney. This band is preferably formed of sheet metal and has a series of openings f' therein for the admission of air to the burners, the air passing inwardly through the openings f and downwardly to the burners. The ring or band F is provided with set-screws F'', by means of which the globe, as I, is secured in position. The globe I is preferably provided with an opening i in the bottom to permit the escape of water which may be condensed therein, and air may also, though not necessarily, enter here.

The shade H is supported by the arms G, which are secured to the globe-supporting ring F, projecting outwardly therefrom. The ends of these arms G are turned down to receive the thumb-screws g, by which the shade is secured.

By thus arranging the parts they are all supported from the central chimney, and the shade or globe may be readily removed for the purpose of cleaning or affording access to the burners.

About the upper part of the lamp is a cylindrical casing J'. The upper portion of this casing is preferably imperforate, but may, if desired, be provided with ornamental perforations, as is common in structures of this class. The lower end is preferably flared outwardly and is supported a short distance above the band F to allow the free passage of

air to the burners. The lower part of the casing is also preferably provided with openings j', through which the valves b of the burners may be manipulated, and is slotted at one side to receive the valve-lever D' and the pilot-light valve e''. The casing J' is preferably supported from the shade or deflecting-plate, which is arranged upon the supply-pipe C, resting upon the coupling C'. The casing J' is provided with an outturned flange at its upper end to receive the bolts j', by which it is secured to the shade J. Suitable sleeves j'' are provided for these bolts to keep the parts properly spaced and form air-outlets for the chimney.

The mantles K, which are cup-like in form, are suspended by the mantle-supports f'', which are arranged through suitable perforations in the chimney and are secured by suitable set-screws to the rivets f'', through which they are arranged. I thus support the mantles in a very secure and rigid manner and very simply.

In operation the heated air and gases from the burners pass up through the chimney and out under the shield J above the same. The burner and gas-delivery pipes are protected from these heated gases so that they do not become unduly heated, which is very apt to cause back lighting. The burners are fully protected from draft, so that the flame is properly directed to heat the entire mantle, and at the same time the desired supply of air is insured owing to the draft which is set up through the chimney. The burners being grouped about the chimney are in position so that the fresh air is drawn up through the mantles, thereby insuring perfect combustion of the gases.

By arranging the burners in an inverted position there is nothing below the burners to obstruct the light or to cast shadows. By thus arranging the parts I secure a lamp the candle-power of which is greatly in excess of the incandescent lamps which have heretofore come to my knowledge.

I have illustrated my improved gas-lamp in detail in the form preferred by me on account of its structural simplicity and economy and convenience in operation and adjustment. I am, however, aware that it is capable of very great variation in structural details without departing from my invention.

Having thus described my invention, what I claim as new, and desire to secure by Letters Patent, is—

1. In a gas-lamp, the combination with a gas-delivery pipe, of a T-coupling member; a chimney having an outwardly-projecting flange at its lower end, secured to said coupling member; a gas-delivery ring arranged about said chimney; connections therefor to said coupling member; downwardly-directed burner-nozzles arranged on said gas-delivery ring; burner-tubes arranged through said

- flange of said chimney; downwardly-directed burner-tips arranged on the lower ends of said tubes; needle-valves for said burner-nozzles arranged through said gas-delivery ring; a globe; a globe-supporting ring or band having an outwardly and downwardly turned flange on its upper end, resting upon and secured to the flange of said chimney, said band having openings therethrough for the admission of air to the burners; a casing for the upper portion of said chimney, having openings therein through which the valves of said burner-nozzles may be manipulated; and a deflector-plate arranged above said chimney, to which said casing is secured, for the purpose specified. 5
2. In a gas-lamp, the combination with a gas-delivery pipe, of a T-coupling member; a chimney having an outwardly-projecting flange at its lower end, secured to said coupling member; a gas-delivery ring arranged about said chimney; connections therefor to said coupling member; downwardly-directed burner-nozzles arranged on said gas-delivery ring; burner-tubes arranged through said flange of said chimney; downwardly-directed burner-tips arranged on the lower ends of said tubes; needle-valves for said burner-nozzles arranged through said gas-delivery ring; a globe; a globe-supporting ring or band having an outwardly and downwardly turned flange on its upper end, resting upon and secured to the flange of said chimney, said band having openings therethrough for the admission of air to the burners; and a casing for the upper portion of said chimney, for the purpose specified. 10
3. In a gas-lamp, the combination of a chimney having an outwardly-projecting flange at its lower end; a gas-delivery ring arranged about said chimney; downwardly-directed burner-nozzles arranged on said gas-delivery ring; burner-tubes arranged through said flange of said chimney; downwardly-directed burner-tips arranged on the lower ends of said tubes; needle-valves for said burner-nozzles arranged through said gas-delivery ring; a globe; a globe-supporting ring or band carried by said chimney, having openings therethrough for the admission of air to the burners; mantles; supports therefor arranged through the flange of said chimney; and means for securing said mantle-supports to said globe-supports, for the purpose specified. 15
4. In a gas-lamp, the combination of a chimney having an outwardly-projecting flange at its lower end; a gas-delivery ring arranged about said chimney; downwardly-directed burner-nozzles arranged on said gas-delivery ring; burner-tubes arranged through said flange of said chimney; downwardly-directed burner-tips arranged on the lower ends of said tubes; needle-valves for said burner-nozzles arranged through said gas-delivery ring; a globe; a globe-supporting ring or band carried by said chimney; means for securing said mantle-supports to said globe-supports; and a casing for the upper portion of said chimney, for the purpose specified. 20
5. In a gas-lamp, the combination of a chimney having an outwardly-projecting flange at its lower end; a gas-delivery ring arranged about said chimney; downwardly-directed burner-nozzles arranged on said gas-delivery ring; burner-tubes arranged through said flange of said chimney; downwardly-directed burner-tips arranged on the lower ends of said tubes; needle-valves for said burner-nozzles arranged through said gas-delivery ring; a globe; and a globe-supporting ring or band carried by said chimney, having openings therethrough for the admission of air to the burners; and a casing for the upper portion of said chimney, for the purpose specified. 25
6. In a gas-lamp, the combination of a chimney having an outwardly-projecting flange at its lower end; a gas-delivery ring arranged about said chimney; downwardly-directed burner-nozzles arranged on said gas-delivery ring; burner-tubes arranged through said flange of said chimney; downwardly-directed burner-tips arranged on the lower ends of said tubes; needle-valves for said burner-nozzles arranged through said gas-delivery ring; a globe; a globe-supporting ring or band carried by said chimney, having openings therethrough for the admission of air to the burners; mantles; supports therefor arranged through the flange of said chimney; and means for securing said mantle-supports to said globe-supports, for the purpose specified. 30
7. In a gas-lamp, the combination of a chimney having an outwardly-projecting flange at its lower end; a gas-delivery ring arranged about said chimney; downwardly-directed burner-nozzles arranged on said gas-delivery ring; burner-tubes arranged through said flange of said chimney; downwardly-directed burner-tips arranged on the lower ends of said tubes; and needle-valves for said burner-nozzles arranged through said gas-delivery ring, for the purpose specified. 35
8. In a gas-lamp, the combination of a chimney having an outwardly-projecting flange at its lower end; a gas-delivery ring arranged about said chimney; inverted burners arranged through said flange; a globe; a globe-supporting ring or band carried by said chimney; mantles; supports therefor arranged through said flange of said chimney; and means for securing said mantle-supports to said globe-supports; for the purpose specified. 40
9. In a gas-lamp, the combination of a chimney having an outwardly-projecting flange at its lower end; a gas-delivery ring arranged about said chimney; inverted burners arranged through said flange; a globe; a globe-supporting ring or band carried by said chimney; mantles; supports therefor arranged through said flange of said chimney; and means for securing said mantle-supports to said globe-supports; for the purpose specified. 45

arranged through said flange; a globe; and a globe-supporting ring or band carried by said chimney, for the purpose specified.

10. In a gas-lamp, the combination of a chimney having an outwardly-projecting flange at its lower end; a gas-delivery ring arranged about said chimney; inverted burners arranged through said flange; and mantles for said burner, for the purpose specified.
11. In a gas-lamp, the combination with a gas-delivery pipe of a chimney having an outwardly-projecting flange at its lower end; an inverted burner arranged through said flange; a mantle therefor; a globe; and a globe-supporting ring carried by said chimney, for the purpose specified.

12. In a gas-lamp, the combination with a gas-delivery pipe of a chimney having an outwardly-projecting flange at its lower end; an inverted burner through said flange; and a mantle for said burner, for the purpose specified.

13. In a gas-lamp, the combination with a gas-delivery pipe, of an unobstructed draft-chimney; an inverted burner arranged through the wall of said chimney, with its tip below and its valves outside of the same; a mantle for said burner; a globe adapted to inclose said burner; and a globe-supporting ring carried by said chimney, for the purpose specified.

14. In a gas-lamp, the combination with a gas-delivery pipe, of an unobstructed draft-chimney; an inverted burner arranged through the wall of said chimney, with its tip below and its valves outside of the same; and a mantle for said burner, for the purpose specified.

15. In a gas-lamp, the combination with a gas-delivery pipe, of a gas-delivery ring connected thereto; a chimney arranged through said ring; a group of inverted burners arranged through the wall of said chimney, connected to said ring; mantles for said burners; and a valve for said gas-supply pipe located adjacent to said ring, for the purpose specified.

16. In a gas-lamp, the combination with a gas-supply pipe, of a gas-delivery ring connected thereto; a chimney arranged through said ring; a group of inverted burners arranged through the wall of said chimney, connected to said ring; and mantles for said burners, for the purpose specified.

17. In a gas-lamp, the combination with a gas-delivery pipe, of a chimney having a flange at its lower end, of an inverted burner arranged through said flange; a mantle therefor; and a depending mantle-support arranged through said flange, for the purpose specified.

18. In a gas-lamp, the combination of a central draft-chimney provided with an outwardly-projecting flange at the bottom; a gas-supply; a plurality of inverted burners

grouped about said chimney, arranged through said flange, with their tips below and their valves without the same, coacting for the purpose specified.

19. In a gas-lamp, the combination of a central chimney having a downwardly and outwardly projecting flange at the bottom; inverted burners, the tips of which are arranged beneath the said flange with their valves above the same outside of the chimney; mantles for said burners; and a supporting-ring secured to said flange for the attachment of the globe and perforated for the admission of air downwardly to the said burner-tips, coacting for the purpose specified.

20. In a gas-lamp, the combination with a gas-delivery pipe, of a central unobstructed draft-chimney; a plurality of inverted burners having mantles grouped about said chimney and arranged through the wall thereof, with the mantles beneath the bottom of the chimney and their controlling-valves outside thereof, coacting for the purpose specified.

21. In a gas-lamp, the combination with a gas-delivery pipe of an unobstructed draft-chimney provided with an outwardly-projecting flange at its lower end; an inverted burner having a mantle arranged through said flange of said chimney, with its tip and mantle below the bottom of the chimney and the controlling-valve thereof arranged outside of the chimney, coacting for the purpose specified.

22. In a gas-lamp, the combination with a gas-delivery pipe, of an unobstructed draft-chimney; and an inverted burner arranged through the wall of the chimney, with its tip beneath the bottom of the chimney and the controlling-valve outside thereof, coacting for the purpose specified.

23. In a gas-lamp, the combination of a central chimney; a tubular ring surrounding the same for supplying gas; downwardly-projecting burners secured to said ring, the tips of which project beneath the bottom of the chimney; mantles for said chimney; a globe-supporting ring secured and carried by said chimney; and an outer casing around the upper part of said chimney and connections, coacting for the purpose specified.

24. In a gas-lamp, the combination of a chimney; a plurality of inverted gas-burners grouped about the same; an inverted pilot-burner having a laterally-directed tip; a gas-supply pipe to which said pilot is connected; and a valve for controlling the supply of gas to the burner, having a main passage and an auxiliary or pilot passage, said pilot-passage being arranged so that it delivers to the pilot during the opening movement of the main valve, whereby the pilot is flashed to ignite the main burners, for the purpose specified.

25. In a gas-lamp, the combination of the main burner; a pilot-light; a gas-supply valve having a main passage and an auxiliary passage arranged to deliver to the pilot only during the opening movement of the valve for opening the main passage, whereby the pilot is flashed; a by-pass for said pilot; a ratchet on said valve; a pivoted lever; a pawl on said lever arranged to coact with said ratchet; and a spring for returning said lever to its initial position, for the purpose specified.
26. In a gas-lamp, the combination with a depending gas-supply pipe; a chimney sup-
- ported thereon; an inverted burner arranged through the wall of said chimney, with its tip below, and valves outside of the same; a mantle for said burner; and an outer casing suitably mounted on said gas-supply pipe, for the purpose specified.

In witness whereof I have hereunto set my hand and seal in the presence of two witnesses.

ALFRED H. HUMPHREY. [L. s.]
